[57] **CLAIM**

The ornamental design for a partition-mounted dual combined seat cover dispenser, toilet paper dispenser, and waste receptacle unit, as shown and described.

DESCRIPTION

FIG. 1 is a top, front, and left side perspective view of a partition-mounted dual combined seat cover dispenser, toilet paper dispenser, and waste receptacle unit showing my new design;

FIG. 2 is a right side elevational view thereof;

FIG. 3 is a bottom plan view of thereof;

FIG. 4 is a rear elevational view thereof;

FIG. 5 is a left side elevational view; and,

FIG. 6 is a top plan view thereof.

The fragmentary broken-line disclosure of a toilet stall partition in the views is for illustrative purposes only and forms no part of the claimed design.
